BUTTER-CHIP MAKER

Maurice J. Weinberg, New York, N. Y.

Application May 12, 1939, Serial No. 273,347

7 Claims. (Cl. 31—42)

The present invention relates to a new and improved apparatus for forming butter chips or patties.

An important object of the invention is to provide a device, preferably for household use, that will produce butter in chip form and simultaneously ornament and/or emboss each formed chip.

A further object of the invention resides in the provision of a butter chip forming and ornamenting device comprising inner and outer frames supported in slidable relation, the inner frame forming with the upper portion of the outer frame a butter receiving chamber. The end walls of the outer frame are formed with a pair of aligned openings for permitting removal of the inner frame after ornamentation of the butter supported within the receiving chamber has been effected. The inner frame comprises top, bottom and side walls, the end walls of said frame being open for cooperation with the openings formed in the end walls of the outer frame when desiring to move one frame relative to the other.

The invention will be fully and comprehensively understood from a consideration of the following detailed description when read in connection with the accompanying drawing which forms a part of the application.

In the drawing:

Figure 1 is a transverse sectional view of the device and illustrating a slab of butter in the process of ornamenting and chip making.

Figure 2 is a vertical sectional view taken substantially on line 2—2 of Figure 1.

Figure 3 is a fragmentary vertical sectional view illustrating the manner of removing the base frame from the outer frame.

Figure 4 is a perspective view, partly in section, of a modified form of frame construction, and

Figure 5 is a vertical sectional view of the form illustrated in Figure 4.

The herein described device is primarily adapted for household use when it is desired to form a limited number of butter chips or patties from a predetermined supply of butter. It is to be understood that the ornamenting head may be formed with various letters and characterizations significant of the user.

Referring to the drawing for a more detailed description thereof, and particularly to Figures 1 to 3 inclusive, it will be noted that there are provided an inner and outer frame 7 and 8 respectively, each frame being substantially rectangular-shaped, with the inner frame 7 being slidably held relative to the outer frame 8. The frames 7 and 8 are preferably formed of relatively thin

light weight metal or similar material so that the combined thickness of the two frames when supported one within the other will provide a relatively rigid structure.

The frame 7 comprises top and bottom walls 9 and 10, respectively, and side walls 11 and 12, respectively, with the ends of said frame being open whereby there is formed a substantially hollow rectangular-shaped structure. The outer frame 8 comprises side walls 13 and 14, respectively, a bottom wall 15 and end walls 16 and 17, respectively. The side and end walls of the frame 8 are formed with an outwardly extending flange 18 for guiding and receiving the impresser head generally designated by the reference numeral 19. The flange 18 also serves as a finger support when moving frame 7 relative to frame 8 and in addition adds structural strength to said frame. The function of the impresser head 19 and the flange 18 is the same as that described in my Patent #2,147,684 issued February 21, 1939. When the frames 7 and 8 are united in the manner shown in Figures 1 and 2 of the drawing, the upper ends of the side and end walls of the outer frame 8 extend above the top wall 9 of the inner frame 7 and combine to form a receiving chamber 20 for a slab of butter 21 sliced from a print of butter or from butter in bulk form, the slab of butter being of a form and size to fit within the outer frame 8 and to rest upon the top wall 9, said top wall thus forming a supporting surface.

The bottom wall 15 of the outer frame 8 is provided with eccentrically formed rib members 31 and 32 respectively, which cooperate with correspondingly formed grooves 33 and 34, respectively, formed in the bottom wall 10 of the inner frame 7 when said frames are arranged in the manner shown in Figure 1 of the drawing. After the formation of the butter chips by the impresser head 19, the inner frame 7 is removed from the outer frame 8, and in order that the formed butter chips may be lifted from the supporting surface 8, the inner frame 7 is placed within the outer frame 8 in a position reversed to that shown in Figure 1 of the drawing. As afore-indicated, the rib members 31 and 32, respectively, are formed on the bottom wall 15 of the outer frame 8, said rib members being so positioned that one of the members is at a greater distance from the intersection of the axes of the bottom wall taken at right angles to each other than the other rib member. Due to this formation, when the inner frame 7 is placed within the outer frame 8 in a position reverse to that shown in Figure 1 of the drawing, the

plain surface of the bottom wall 10 of the inner frame will rest upon said ribs, thereby supporting the bottom of the inner frame substantially entirely spaced from the bottom of the outer frame to bring the supporting surface 9 substantially flush with the flanged portion 18. By means of a suitable implement, the formed butter chips may then be lifted from the supporting surface 9. If desired, however, the bottom walls 10 and 15 of the frames 7 and 8, respectively, may be formed of a relatively flat surface by omitting the ribs and grooves, in which case said bottom walls would rest one upon the other.

The impresser head 19 is of substantially the same shape as the outer frame 8 and is of a size to fit over the flanges 18. The inner surface of the impresser head is formed with ornamenting means 22 and is also provided with integrally formed extending cutting members 23 for dividing the print of butter into a number of equal sized chips as explained in the above mentioned patent, and, since the use and operation of the said head is the same as described in the patent, it is not believed that a further description thereof is necessary at this time.

The end walls 16 and 17 of the outer frame 8 are formed with upper and lower aligned openings 24 and 25, respectively, said openings being preferably formed in substantially the central portion of the end walls. After ornamenting and cutting the chips from the slab of butter by means of the impresser head 19, said head is manually lifted from the outer frame 8. Due to the adhesive qualities of butter, it is necessary in order to release the head to impart a rocking motion thereto when lifting the same and to also prevent lifting of the inner frame 7. For this reason the lower opening 25 is formed in the end walls of the frame 8. As more clearly shown in Figure 1 of the drawing, when removing the impresser head the thumb of one hand is disposed through the opening 25 and rests upon the bottom wall 10 of the frame 7 for securely holding said frame with one hand while lifting the impresser head 19 with the other hand.

The purpose of the upper aligned openings 24 is to permit the insertion of the fingers, as shown in Figure 3 of the drawing, beneath the top wall 9 of the inner frame 7 so as to project said wall above the flange 18 whereby the open end walls of said frame can be engaged by both hands for completely lifting the same from the outer frame 8. The inner frame 7 is then reversed and replaced within the outer frame 8 in the manner previously described. After removal of the inner frame from the outer frame, the ornamented chips are lifted from the supporting surface 9 by any desired means. As is to be understood a finger of each hand is inserted through the openings 24 with the thumb resting upon the flange 18 and by exerting pressure upwardly by means of the finger, said frame is readily removed.

In Figures 4 and 5 of the drawing, there is disclosed a modified form of the invention which comprises an inner frame 26 and outer frame 27, said frames being substantially rectangular-shaped and formed with side and end walls and adapted to be disposed for sliding relation. It will be noted that the outer frame 27 has open top and bottom areas while the bottom portion only of the inner frame 26 is open. In addition to the side and end walls, the frame 26 further includes a top wall 30 which forms a supporting surface for a print of butter, substantially the

same as in the preferred form. The outer frame 27 is provided with an upper flange 28 for accommodating the impresser head 19 and the inner frame 26 is formed with an outwardly extending flange 29 on the bottom thereof upon which rests the outer frame 27. The modified form differs from the preferred form in that the outer frame is lifted to permit removal of the ornamented chips. When lifting the outer frame 27, the flange 29 is engaged by one hand for securely holding the inner or base frame 26. The flange 29 and frame 27 are both held while lifting the impresser head from the flange 28 after the ornamenting and cutting operation has been performed.

From the above description taken in connection with the accompanying drawing, it will be readily apparent that there is provided a relatively simple and inexpensive structure for forming ornamented butter chips. The bottom plates 10 and 15 and the slidably engaging side walls of both frames materially stiffen the structure of the device for adding rigidity thereto. By this construction the device can be manufactured using exceptionally thin material thereby reducing to a minimum the cost thereof. It is, of course, to be understood that the respective sizes of the frames are such as to permit free sliding movement of one frame relative to the other.

Also it will be understood, of course, by those skilled in the art that variations in the hereinabove described device involving the substitution of substantial equivalents for the devices described are intended to be comprehended within the spirit of the present invention and that the invention is capable of extended application and is not confined to the exact showing of the drawing nor to the precise construction described and, therefore, such changes and modifications may be made therein as do not affect the spirit of the invention nor exceed the scope thereof as expressed in the appended claims.

What is claimed is:

1. A device of the character described comprising, an outer frame having upstanding walls, and an inner frame slidably engaging the walls of said outer frame, said inner frame forming with an upper portion of the outer frame a receiving chamber for a print of butter, one or more of the walls of said outer frame being formed with aligned openings for insertion of a finger within the inner frame to hold said frames in one position and to permit urging the inner frame upwardly for disengagement from the outer frame.

2. A device of the character described comprising, an outer frame having upstanding walls, an inner frame slidably engaging the walls of said outer frame, said frames being rectangular-shaped with the bottom wall of said inner frame resting upon the bottom wall of said outer frame, said inner frame having a top wall to provide a supporting surface for a print of butter, a closure member slidably mounted externally of said outer frame, one or more of the walls of said outer frame being formed with aligned openings for insertion of a thumb and finger for holding the device while removing said closure from said outer frame and to permit disengagement of said inner frame from said outer frame.

3. A device of the character described comprising, an outer frame having upstanding walls, an inner frame slidably engaging the walls of said outer frame, the bottom wall of said outer frame being formed with projecting rib members, the bottom wall of said inner frame being formed

with grooved portions, said rib members being at such varying spaced relation to the side walls that in one position of the inner frame with respect to the outer frame said rib members 5 will rest within the grooves and in another position with respect thereto the ribs will support the bottom of the inner frame substantially entirely spaced from the bottom of the outer frame.

4. A device of the character described comprising, an outer frame having a bottom wall and side walls, an inner frame having a bottom wall and side walls slidably engaging the walls of the outer frame, rib members on the bottom wall of the outer frame, one of said rib members 10 being at a greater distance from the intersection of the axes of the bottom wall taken at right angles to each other than another rib member, the bottom wall of said inner frame being provided with grooves corresponding in location 15 to the rib members whereby when the inner frame is placed within the outer frame in one position with respect thereto the rib members will rest within the grooves and in another position with respect thereto the ribs will support 20 the bottom of the inner frame substantially entirely spaced from the bottom of the outer frame.

5. A device of the character described comprising, an outer frame having a bottom wall and 25 side walls, an inner frame having a bottom wall and side walls slidably engaging the walls of the outer frame, projections on the bottom wall of the outer frame, one of said projections being at a greater distance from the intersection of

the axes of the bottom wall taken at right angles to each other than another projection, the bottom wall of said inner frame being provided with receiving means corresponding in location to the projections whereby when the inner 5 frame is placed within the outer frame in one position with respect thereto the projections will rest within the receiving means and in another position with respect thereto the projections will support the bottom of the inner frame substantially 10 entirely spaced from the bottom of the outer frame.

6. A device of the character described comprising, an outer frame having upstanding walls, and an inner frame slidably engaging the walls 15 of said outer frame, said inner frame forming with an upper portion of the outer frame a receiving chamber for a print of butter, one or more of the walls of said outer frame being formed with openings for insertion of a finger 20 within the inner frame when moving one frame relative to the other.

7. A device of the character described comprising, an outer frame having upstanding walls, and an inner frame slidably engaging the walls 25 of said outer frame, said inner frame forming with an upper portion of the outer frame a receiving chamber for a print of butter, one or more of the walls of said outer frame being formed with superposed openings for insertion 30 of a finger within the inner frame when moving one frame relative to the other.
